(**) Term: **14 Years**

(57) **CLAIM**

(21) Appl. No.: **29/241,378**

The ornamental design for a DC to AC power inverter for a vehicle electrical system, as shown and described.

(22) Filed: **Oct. 25, 2005**

DESCRIPTION

(30) **Foreign Application Priority Data**

Apr. 26, 2005 (JP) 2005-012454

FIG. 1 is a front perspective view of a DC to AC power inverter for a vehicle electrical system showing my new design;

(51) **LOC (8) Cl.** **13-02**

FIG. 2 is a rear perspective view thereof;

(52) **U.S. Cl.** **D13/118; D13/110**

FIG. 3 is a front view thereof;

(58) **Field of Classification Search** **D13/110,**

D13/123, 184, 199; 337/186; 361/600,

361/601, 730; 363/141, 142

FIG. 4 is a rear view thereof;

See application file for complete search history.

FIG. 5 is a top plan view thereof;

(56) **References Cited**

FIG. 6 is a bottom plan view thereof;

U.S. PATENT DOCUMENTS

FIG. 7 is a right side elevational view; and,

4,872,102 A * 10/1989 Getter 363/141

FIG. 8 is a left side elevational view thereof.

5,170,336 A * 12/1992 Getter et al. 363/141

The broken lines are shown for illustrative purposes only

D349,682 S * 8/1994 Hunziker D13/110

and form no part of the claimed design.

D413,567 S * 9/1999 Person et al. D13/110

The broken line(s) which define the bounds of the claimed

5,949,640 A * 9/1999 Cameron et al. 361/600

design form no part thereof.

D426,810 S * 6/2000 Wei D13/110

D427,146 S * 6/2000 Wei D13/110
